SWITCH-STACK ASSEMBLY

Callard Livingston, Chicago, Ill., assignor to
Comar Electric Co., Chicago, Ill.

Application May 10, 1941, Serial No. 392,857

3 Claims. (Cl. 200—166)

This invention relates to a switch stack assembly of the type consisting of a plurality of elongated spring leaf switch blades secured at one end between insulating pieces or wafers arranged in a stack with the switch blades sandwiched in between alternate insulating pieces. This kind of switch is sometimes referred to as a jack switch.

The principal object of the invention is the provision of means for automatically taking up any shrinkage or looseness between the insulating wafers whereby to prevent looseness of the switch blades mounted therebetween and consequent inaccuracy of alignment between the contact point on the switch blades, or faulty electrical contacting between such contact points when one or more of the blades is operated in switching movement.

Since the stack of insulators with the switch blades secured therebetween is usually mounted by means of one or more screws passing through the entire assembly of wafers and switch blades, it is necessary to employ an insulating sleeve around the mounting screw or screws to prevent short-circuiting the portions of the switch blades through which these screws pass, and it frequently happens that owing to slight variations in the thickness of the insulating wafers or in the length of insulating sleeve cuts, the end portions of said sleeves may protrude slightly above the stack of insulating wafers—that is above the switch stack assembly, and trouble is at once encountered because the mounting screws cannot be turned up tightly against the stack of insulating wafers, but instead, the screw bears against the protruding portion of the sleeve, with a consequent looseness of the switch stack assembly.

A further important object of the invention is therefore to provide in addition to the aforesaid automatic take-up means for shrinkage and the like, a means for obviating the difficulties arising from slight variations in dimension of the wafers and the sleeves.

A further and important object of the invention is provision in a switch stack assembly, of a resilient header member which will bear down against a plurality of points on the topmost insulating wafer of the switch stack; which will automatically compensate for any looseness between the wafers of the switch stack due to shrinkage and the like; and which will also permit the application of adequate pressure on the switch stack by the mounting screws notwithstanding the fact that the insulating sleeves for the mounting screws may protrude slightly above the top level of the stack due to various kinds of inaccuracy in dimension.

Other objects and novel aspects of the invention reside in details of construction and operation of the preferred embodiment now to be de-

scribed in view of the annexed drawing, in which:

Fig. 1 is a partially exploded perspective of the novel switch stack assembly;

Fig. 2 is a transverse section through the switch stack assembly, showing a protruding insulating sleeve;

Fig. 3 is another transverse section through the switch stack showing the action of the spring header with a properly dimensioned sleeve;

Fig. 4 is an enlarged perspective of the improved spring header and take-up member shown in the preceding figure;

For purposes of illustration, a conventional type of jack switch is shown in Fig. 1, and is there mounted on a metal mounting shelf or member 9, the switch including a plurality of elongated leaf spring blades 10 and 11 mounted at one end between alternate insulating blocks or wafers 13.

The mounting ends of these switch blades are provided with one or more holes, corresponding to similarly located holes in each of the wafers 13, through which are passed tubular insulating sleeves 12 of fiber or the like, including hard rubber.

The blades and insulating wafers 13 constitute a switch stack assembly, and in order to hold the same in assembled relation upon the shelf 9, there are provided one or more mounting screws 14 adapted to pass through the sleeves 12 and thread into the mounting member or shelf 9 (see Figs. 2 and 3 also). The sleeves 12 prevent the screws 14 from making electrical contacts with any portion of the blades 10, thereby to prevent short circuits between the blade elements, it being understood that in the simple switch structure shown in Fig. 1 only two switch blades are shown, whereas in practice it is customary to use a larger number of such switch blades.

In Fig. 2, there is shown to exaggerated scale a portion 12a of one of the insulating sleeves projecting above the uppermost insulating wafer 13a, and it will be apparent that if the mounting screw 14 were turned down tightly (without the intermediary of any kind of washer or take-up device) the head of the screw would bear against the end of the protruding portion 12a and would exert no pressure whatever against the topmost wafer 13a of the assembly. Obviously under such

conditions the switch stack assembly would be loose and would be wholly unsatisfactory from an electrical or mechanical standpoint for use as a switch, as will be readily recognized by those skilled in the art since it is imperative that the switch blades 10 and 11 be accurately aligned and permanently affixed in order that they may engage and disengage accurately and promptly and firmly in making and breaking electrical circuits.

In practice it has been found impossible, from 60 an economical production standpoint to prevent

variations in dimensions either of the wafers 13 or in the length of the sleeve 12, and it is therefore a very commonly encountered difficulty in the manufacture of such switch stacks to find either imperfectly secured assemblies, or to be faced with the necessity for rejecting the imperfectly fitting sleeve, thus increasing the manufacturing costs (which must be closely calculated on such a small item).

The invention provides means in the nature of a spring header element generally indicated at 15, Figs. 1 and 4, and which is in the preferred shape of a rectangle of spring metal bowed transversely to provide an arcuate conformation as indicated at 15b in Fig. 4. One or more holes 15a are provided to receive the mounting screws 14 in alignment with sleeve portions 12.

As a general rule the protruding sleeve portions 12a (Fig. 2) generally do not extend more than two or three-thousandths of an inch above the surface of the top wafer 13a, although the showing in Fig. 2 is considerably exaggerated in order to bring out the nature of the difficulty which the present invention overcomes.

Therefore, the degree to which the header members 15 are bowed or sprung in giving them the aforesaid arcuate conformation, need only be sufficient to give a springing range of about fifty-thousandths of an inch down to approximately zero thousandths, when the header member would be substantially flat, corresponding to a perfectly flush sleeve end 12a. In practice it is not necessary to drive the header member 15 down flat even though the sleeve may fit perfectly as illustrated in Fig. 3, wherein the degree of arcuateness or bowing left in the header member 15 is more than would exist in practice, the bowing indicated at 15b being exaggerated for purposes of clarity of illustration. Actually the header member 15 would be flattened out considerably more than shown in Fig. 3.

The important thing in the action of the header member 15 is that all along the opposite parallel edge portions 15c (Figs. 2 and 3), there be substantial bearing pressure against the upper surface of the top insulating wafer 13a, even when there be a protruding portion 12a of the sleeve.

It will be apparent from an examination of Fig. 4, for example, that the improved header member 15 may be very inexpensively manufactured by a stamping or punching process, and yet the general annoyance and potential increase in manufacturing costs of switch stack assemblies is completely obviated by the use of such a means. Moreover, the general operating stability of the switch stack is improved throughout its useful life because shrinkage or settling of the insulating wafer elements 13, which would otherwise cause a loosening up of the switch blades, is automatically compensated for by the constant pressure exerted by the header member, and this would be true whether the shrinkage or looseness in fit were to result from a slow aging of the insulating material itself, or from more abrupt and frequent variations in expansion and contraction due to temperature changes, it being pointed out that switches of this type are commonly used in mechanisms which cause frequent changes in temperature in the immediately surrounding air, and unless the switch stack can be firmly secured in position, such variations are a sure cause of future trouble.

It will be recognized that the shape and con-

formation of the header member may be altered to suit the peculiarities or requirements of a given switch stack assembly or other adaptation, and the invention is therefore not to be limited to specific details of shape, form or location or application, except as may be necessarily imported by the appended claims.

Having thus described my invention, what I claim as new and desire to protect by Letters Patent of the United States is:

1. In combination with a switch stack assembly of the class described, an accommodation header comprising a piece of spring metal bowed to provide a concavo-convex configuration, and provided with one or more holes for passage of a mounting screw or the like extending into said assembly, said header being adapted for mounting on the topmost member of the stack with its concavity facing said member and edgewise portions bearing by urging of said screw against the stack with space available in the concavity for accommodation of protruding portions of the stack, substantially as set forth.
2. In a switch stack assembly of the type including one or more elongated spring switch blades mounted between two or more insulating members, and secured to a mounting member by means of one or more screws passed through said blade or blades and said insulating members and surrounded by an insulating sleeve likewise passing through said blade or blades and insulating members, the combination of a header means adapted to automatically take up looseness between said insulating members and blades and to compensate for ordinary oversize in tolerance in the length of the said sleeve, said means comprising a header member constructed of spring metal or analogous material of substantially rectangular form and bowed transversely with openings therethrough to accommodate mounting screws passing through said sleeve, said header being adapted to overlie the topmost insulating member and to have edge portions pressed against said member by tightening up of said mounting screw or screws with any protruding portion of the sleeve as aforesaid extending into the space beneath the bowed portion of the header immediately surrounding said screw or screws.
3. A switch stack assembly, comprising, in combination, a plurality of switch blades, secured between alternately positioned insulating wafers arranged in a stack, there being one or more insulating sleeves passed through said blades and wafers in said stack to provide a protective passage for a mounting screw, said stack being adapted for mounting on a support by means of screws passed through said sleeves, together with a header member in the form of an elongated piece of metal bowed transversely of its length and provided with mounting holes for alignment with said sleeves, said screws being passed through said mounting holes into said sleeves and turned up against said header to spring the latter against the topmost insulating wafer in said stack, whereby to provide a concavity between the underside of the header and said topmost wafer and to cause edgewise portions of the header to bear against the latter when said screw is turned up, and to provide a space to accommodate oversize in length of said sleeves.

CALLARD LIVINGSTON.

DISCLAIMER

2,277,443.—*Callard Livingston*, Chicago, Ill. SWITCH-STACK ASSEMBLY. Patent dated March 24, 1942. Disclaimer filed September 3, 1942, by the inventor, and the assignee, *Comar Electric Company*.

Hereby limit claims 1, 2, and 3 of said patent to that form of header which is concavo-convex and in which the curvatures of concavity and convexity are substantially uniform and not interrupted by flat surfaces; that form of header which is rectangular and provided with a central flat area with marginal portions sloping downwardly and outwardly from said flat area and either partially or totally surrounding said flat area, being specifically disclaimed hereby.
